UNITED STATES PATENT OFFICE.

ISAAC A. BAUM, OF CHICAGO, ILLINOIS.

METAL FRAMING.

Application filed April 27, 1928. Serial No. 273,304.

My invention relates to building construction and particularly to a novel metal frame arrangement for doors and similar wall openings.

5 An object of my invention is to provide simple means for effecting a rigid connection between metal frame elements and a tile or other masonry wall. In construction heretofore suggested the metal frame has been 10 held against lateral movement relative to a masonry wall by means of flat lugs or ears struck out from or welded to the sides of the metal members. The flat surfaces projected rearwardly of the frame, while performing 15 the expected function of holding the frame relative to the wall, are objectionable in that plaster will not adhere thereto; and as the plaster is necessarily carried over the metal frame to the marginal edge thereof, 20 there is a relatively large expanse of plaster that is unsupported by adherence.

To avoid this difficulty and to prevent weakening of the frame member by striking out the lugs from the web thereof, I provide 25 loops of wire that may be firmly welded to the sides of the frame member and that will perform the function of positioning and holding with certainty.

In addition, the construction described 30 serves to greatly simplify the steps incident to the anchoring the frame elements against movement outwardly from the edge of the wall. The anchoring device may directly engage the wire loops, and, if desired, may be formed permanently in place, thus positively 35 assuring the anchoring of the frame member regardless of any skill or intention on the part of the workman.

The invention will be more readily understood by reference to the accompanying 40 drawings, in which—

Fig. 1 is a side elevation of a frame wire lug and anchor arrangement constructed in accordance with my invention;

45 Fig. 2 is a sectional view on line 2—2 of Fig. 1;

Fig. 3 is an elevation from the rear of a modified form of the invention; and

Fig. 4 is a sectional view on line 4—4 of 50 Fig. 3.

In the drawings, and referring particularly to Figs. 1 and 2, I have illustrated a metal frame member of generally channel shape comprising a web 10, side flanges 11 and marginal flanges 12. The latter terminate in rebent portions 13 that constitute

plaster anchors, and the angle of which, with the flanges 12, constitute a plaster ground. These frame members serve to outline a wall opening and are adapted to receive wood or metal trip in the usual manner.

To the sides of the side flanges 11, I weld continuous lengths of wire bent into zig-zag form, thereby forming adjacent oppositely projecting loops of wire. The loops 14 are welded to the sides of the flanges 11 while the loops 15 project beyond the edges thereof and constitute side stops for engagement with the sides of the tile 16 or other forms of walls.

Preferably the wires are bent to provide the straight portions 17 spaced at centers corresponding to the height of standard tiles; or if brick is used the straight portions will be so located that a joint in the brick will always come at some point in the extent of the straight portions. To the straight portions of the wire is secured a cross wire 18 acting as an anchor. The wire 80 constituting the anchor is preferably twisted around the straight portions 17, sufficiently loosely to enable the anchor to be moved up and down and while being shipped to lie flat against the sides of the channel if 85 desired. Preferably also the anchor will be curved or looped as shown in order to project the anchor portion as far as possible inwardly from the outer edge of the tile.

It will be noted that by reason of this arrangement the workman cannot fail to anchor the frame members inasmuch as the anchor will be in his way unless he positions it as shown in the drawings.

In the modified form shown in Figs. 3 95 and 4, the frame member is of integral form and comprises a sheet of metal bent to provide a jamb 19, a stop 20, molding 21 and plaster anchor 22. To the inner face of the jamb is welded at intervals the loops 23 of 100 wire having rearwardly extending projections 24 that function as means for laterally positioning the frame relative to the wall. The vertically extending portions of the loops are positioned to overlie the groove provided by forming the door stop, thus constituting a slot having a restricted opening adapted to receive an anchor 25 in the form of a flat strip having notches 26 in its sides and a T head 27 occupying the groove 110 within the stop.

The wire loops may be very simply formed

and easily applied by welding. They are of economical construction and of light weight providing nevertheless ample lateral resistance for the purpose required.

5 Obviously the desired result may be accomplished by bending and applying wire elements in other forms than those illustrated and I do not wish to be limited except as indicated in the appended claims.

10 I claim:

1. In combination, a steel frame member and wires bent into loops and welded to said frame member and having portions projecting rearwardly from said member to lie 15 alongside of a masonry wall to hold the member against lateral movement relative to said wall.

2. In combination, a steel frame member and wires bent into loops and welded to said 20 frame member and having portions projecting rearwardly from said member to lie alongside of a masonry wall to hold the member against lateral movement relative to said wall, and a wall anchor engaging 25 said wire loops.

3. In combination, a metal frame member and wires bent into zigzag form and secured to the sides of said frame member, portions 30 of the wire projecting rearwardly from the frame and engaging the sides of a masonry wall, to serve as means for holding the frame

against lateral movement relative to said wall.

4. In combination, a metal frame member and wires bent into zigzag form and secured 35 to the sides of said frame member, portions of the wire projecting rearwardly from the frame and engaging the sides of a masonry wall, to serve as means for holding the frame against lateral movement relative to said 40 wall and a wall anchor connected to said projecting portions.

5. In combination, a metal frame member and wires welded to the said frame member and projecting rearwardly therefrom to act 45 as means for laterally holding the frame relative to a wall and an anchor permanently connected to said wire members and adapted to lie in the joints between courses of masonry constituting said wall. 50

6. In combination, a metal frame member and wires welded to the said frame member and projecting rearwardly therefrom to act as a means for laterally holding the frame relative to a wall and an anchor 55 permanently connected to said wire members and slidable relative thereto to lie between the courses of masonry constituting said wall.

In testimony whereof I have affixed my 60 signature.

ISAAC A. BAUM.
